UNITED STATES PATENT OFFICE.

GEORGE FRAZER, OF WILLIAMSBURG, INDIANA.

WAGON-JACK.

SPECIFICATION forming part of Letters Patent No. 361,997, dated April 26, 1887.

Application filed January 8, 1887. Serial No. 223,759. (No model.)

To all whom it may concern:

Be it known that I, GEORGE FRAZER, a citizen of the United States, residing at Williamsburg, in the county of Wayne, State of Indiana, have invented certain new and useful improvements in Wagon-Jacks, of which the following is a specification, reference being had therein to the accompanying drawings.

My invention relates to that class of machines used to raise the axles of wagons and other objects by hand-power.

My invention consists in the devices herein described, constructed and operating as set forth and claimed.

15 In the drawings, Figure 1 is a perspective view of my improved machine in a vertical position. Fig. 2 is a top plan view with a portion of the frame in cross-section. Fig. 3 is a side longitudinal section on a central line running from top to bottom, shown in a horizontal position.

In Fig. 1, A A represent a vertical frame composed of two upright pieces of timber parallel and firmly secured to each other.

25 B B are arms which have a common axis on a transverse horizontal rod or journal, a, which is supported at each end in ears or brackets a' a', secured to the front side of the framing A A. The front ends of the arms B

30 B have a bolt, c, passing through them, which secures them to the hand-lever C and which serves as an axis upon which said hand-lever C is permitted to oscillate.

D is a notched wheel, which is allowed to revolve on the journal a, situated centrally between the vertical pieces forming the framing A A, and near the top of the same, and is provided on its periphery with a series of triangular projections or teeth, 1 2 3 4 5 6, Fig. 3, one of the surfaces of which is at right angles to the circumference of the wheel. Formed upon and solid with the wheel D are pinions E E, Figs. 1, 2, and 3, smaller in diameter than the wheel D and revolving with it on the journal a. These pinions E E engage in and actuate the toothed bars b b, which are permitted to slide up and down in the frame A when impelled by the pinions E E.

The bars b b are connected at the top by a cross-head, x, which is placed under the object to be raised.

The hand-lever C has its inner end constructed to fit into the recesses on the wheel D, and has its bearing upon said teeth 1 2 3 4 5 6, successively, as seen in Fig. 3, having an endwise motion allowed by the swinging motion of the arms B B, between which it is permitted to oscillate. When the inner end of the hand-lever is placed in contact with the surface of the tooth 4, as seen in Fig. 3, and a pressure is exerted on the opposite end of the lever, the wheel D is made to revolve, carrying with it the pinions E E, which in their revolution raise the toothed bars b b simultaneously along with the cross-head x and the object under which it is placed.

An open slot, m, is provided in the back of the framing A A, in which is inserted a dog, e, hinged on a pivot, e', and actuated by a spring, s. This dog e is fitted at its upper end to drop into the recesses under the notches or teeth 1 2 3 4, &c., as seen at 9, Fig. 3, by which the wheel D is held in place and the weight sustained at the point where the hand-lever C is withdrawn to be placed in the succeeding notch. By this means a great leverage is attained and smoothly applied to the toothed bars b b in raising, and, by means of the dog e, in holding in position such objects as are sought to be raised.

The bars b b are beveled on their edges, as seen in Fig. 2, to fit the inclined inner surfaces of the spaces in which they move and are retained in framing A A. The arms B B are connected near the front ends by a bar, d.

Having thus fully described my said invention, what I claim as new, and desire to secure by Letters Patent, is—

The combination of the lifting-bar provided with racks b b, the frame A, the shaft a, the pinions and ratchet-wheel thereon, the lever carrying the pawl for operating said ratchet-wheel, and the retaining-dog, all substantially as described.

In testimony whereof I affix my signature in presence of two witnesses.

GEORGE FRAZER.
